UNITED STATES PATENT OFFICE.

SILAS HERBERT MOSHER, OF CHICAGO, ILLINOIS, ASSIGNOR OF ONE-HALF TO CHARLES F. ELMES, OF SAME PLACE.

PACKING.

SPECIFICATION forming part of Letters Patent No. 396,222, dated January 15, 1889.

Application filed March 19, 1888. Serial No. 267,598. (No model.)

To all whom it may concern:

Be it known that I, SILAS HERBERT MOSHER, of Chicago, in the county of Cook and State of Illinois, have invented certain new and useful 5 Improvements in Packing; and I do hereby declare that the following is a full, clear, and exact description thereof, reference being had to the accompanying drawings, and to the letters of reference marked thereon, which form 10 a part of this specification.

This invention relates to an improved packing for use in glands or packing-boxes of pistons and in other similar situations. The invention consists in the matters hereinafter 15 set forth, and pointed out in the appended claims.

The invention may be more readily understood by reference to the accompanying drawings, in which—

20 Figure 1 is a sectional view of a piston-rod and a gland or packing or stuffing-box provided with a packing constructed in accordance with my invention. Fig. 2 is a cross-section of the same taken upon line xx of Fig. 1. Fig. 3 is a perspective view of a single coil of the soft-metal pipe or tubing used for the packing. Fig. 4 shows a straight section of pipe or tubing, partially in side view and partially in section, said pipe or tubing 25 being perforated and filled with a solid lubricating compound in accordance with one part of the invention. Fig. 5 shows a perspective view of ring-shaped piece of perforated tube in readiness for insertion in the gland or packing receptacle.

In the said drawings, A indicates a piston-rod, as of an engine; B, a cylindric head.

C is a gland or stuffing-box, D the cap thereof, and dd screw-bolts for holding the 40 cap in place and for forcing the same into the box to tighten the packing. Said screw-bolts are herein shown as passing through the cap and having screw-threaded engagement with a flange, e, of the stuffing-box in the usual 45 manner.

E indicates the packing as a whole, and ee two coils or pieces of coiled soft-metal pipe or tubing composing the same. In practice one or more than two of such coils may be placed 50 within the gland between the cylindric wall thereof and the piston-rod. The drawings,

however, show a gland of ordinary size and construction, containing two layers or coils of pipe or tubing. Said coils of tubing e are placed within the gland close together or in 55 contact with each other, so that an endwise compression of the mass will result in a lateral expansion or thickening of the same, which will force the inner coil closely into contact with the piston-rod. This result will 60 of course follow from the flattening of the individual pipe-coils under endwise compression of the packing however the coils are arranged with relation to each other; but I prefer to place the convolutions of the inner 65 coil opposite and partially between the meeting surfaces of the other coil, so that when the coils are compressed endwise the inclined surfaces of the coils, in contact with each other, will tend to force the coils apart and 70 to press the inner coil against the piston-rod, even when there is no actual compression of the pipes or tubes themselves. The arrangement of the coils last referred to is clearly 75 shown in the drawings. Whatever be the arrangement of the coils in respect to each other, however, the endwise compression of the entire packing will finally result in the flattening, crushing in, or distortion of the tubes, so that they will more closely fit against 80 the piston-rod and against each other. Such compression of the packing may be continued, furthermore, until the packing is worn out or until it has become too much compacted, or, in other words, too solid for further effective 85 services.

Fig. 3 shows a single coil of soft-metal tubing in readiness for insertion in a stuffing-box. It is of course obvious that a packing consisting of a single coil acts substantially 90 in the same manner as does the packing shown in Fig. 1. In the case of a single coil, however, the lateral pressure of the tubing against the piston is produced solely by the flattening of the coils in one direction and 95 the spreading of the same in the other direction as pressure is applied endwise to the coil by the forcing in of the cap of the stuffing-box.

In compressing the packing the coil in contact with the piston-rod will be flattened 100 against the rod as the pressure upon the pack-

ing is increased, so that the said inner coil will have a bearing-surface of considerable width in contact with the piston-rod. In practice, therefore, the packing is compressed until a sufficient area of the tube composing the inner coil is brought against the piston-rod to make a suitable tight joint. It is obvious, for instance, that when the tube is merely coiled about and against the piston-rod it will have a very narrow surface in bearing thereon, and the packing will be liable to leak under any considerable pressure. By compressing the packing, however, the inner coil will be caused to bear, not only with a greater pressure, but upon a larger area of the piston-rod, so that by suitably graduating the compression of the packing the same may be accurately adjusted to withstand any usual pressure upon the packed joint without producing any unnecessary friction between the parts in bearing with each other.

The packing made as above set forth may be supplied with lubricant in the ordinary manner. It is to be noted, however, that the lubricant accumulating in the spaces between the convolutions of the inner coil will be continually fed to the relatively-narrow surfaces of the coils which are in contact with the piston-rod, so that the construction described greatly facilitates a constant and uniform distribution of the lubricant.

In Fig. 4 I have shown a piece or section, E', of soft-metal tubing which is provided with perforations e' for the escape of lubricant from its exterior to the surfaces to be lubricated. A tube thus made may be employed merely as a means of easily and conveniently conducting lubricant into the interior of the packing and for discharging such fluid lubricant upon the surface of the sliding part in contact with the said packing. The tubing shown in said Fig. 4 is, however, provided with a filling, E², of fibrous material, (shown in said figure as formed by a rope or twisted fibers of approximately the same size as the interior of the tube.) Within the tube is also placed a solid or non-fluid lubricant or lubricating compound. I prefer to use as a lubricant a compound containing tallow or 50 other non-fluid oily substance, and graphite;

but a fatty or oily lubricant alone may be used, or other compounds may be employed. The lubricant thus introduced into the perforated pipe is forced from the perforations as the packing is compressed, and thus affords a constant supply of lubricating material until the packing is no longer compressible.

It will of course be understood that a solid or semi fluid lubricant may be employed with out the fibrous filling. The soft metal perforated tubing containing a lubricant may be made so cheaply as to enable the packing to be removed and replaced by a new tubing at a small expense whenever it is worn out or the supply of lubricant is exhausted.

The fibrous filling has the obvious advantage of preventing the complete collapse of the tube when the latter is compressed. Such filling also acts to absorb and hold a liquid lubricant, so as to enable such lubricant to be used instead of a solid lubricant, such as will be required when the fibrous filling is absent.

In Fig. 5 I have shown a piece, E³, of tubing bent into ring form with its ends abutting. The packing may be made in this way instead of in the form of a coil, as shown in Figs. 1, 2, and 3. The ring shown in Fig. 5 is filled with fibrous and lubricating material, and is perforated in the manner above described.

I claim as my invention—

1. A packing for piston-rods and the like, consisting of soft-metal pipe or tubing surrounding the same, provided with perforations, and filled with a non-fluid lubricant, substantially as described.

2. A packing for piston-rods and the like, consisting of soft-metal pipe or tubing surrounding the same, having perforations, and provided with a fibrous filling saturated with a lubricating substance, all substantially as described.

In testimony that I claim the foregoing as my invention I affix my signature in presence 95 of two witnesses.

SILAS HERBERT MOSHER.
